UNITED STATES PATENT OFFICE

139,317

DESIGN FOR A RING OR THE LIKE

Percy Turk, Houston, Tex.

Application January 29, 1944, Serial No. 112,516

Term of patent 14 years

(Cl. D45—10)

To all whom it may concern:

Be it known that I, Percy Turk, a citizen of the United States, residing at Houston, in the county of Harris and State of Texas, have invented a new, original, and ornamental Design for a Ring or the like, of which the following is a specification, reference being had to the accompanying drawing, forming a part thereof.

Fig. 1 is a top plan view of the ring, showing my new design; and Fig. 2 is a side view thereof.

I claim:

The ornamental design for a ring or the like, as shown.

PERCY TURK.
